UNITED STATES PATENT OFFICE.

DAVID FITZGIBBONS, OF OSWEGO, NEW YORK, ASSIGNOR TO FITZGIBBONS
BOILER COMPANY, OF OSWEGO, NEW YORK.

STEAM-GENERATOR.

SPECIFICATION forming part of Letters Patent No. 742,620, dated October 27, 1903.

Application filed February 10, 1902. Serial No. 93,277. (No model.)

To all whom it may concern:

Be it known that I, DAVID FITZGIBBONS, of Oswego, in the county of Oswego, in the State of New York, have invented new and useful 5 Improvements in Steam-Generators, of which the following, taken in connection with the accompanying drawings, is a full, clear, and exact description.

My invention relates to the combination of 10 a boiler and furnace of peculiar construction which coöperate to produce practically perfect combustion and to generate a high degree of heat.

The essential features are a low furnace 15 having a large or double grate to give a large firing-surface. Over one portion of the furnace extends the boiler. Over the opposite portion is arranged a top of brickwork or other suitable material, provided with flues and inlets for the introduction of fuel and a regulable supply of air. Centrally over the furnace and grate and within the boiler is arranged the combustion-chamber, having a contracted mouth.

25 My invention will be understood by reference to the drawings herewith, in which the reference-numerals of the specification indicate the same parts in both figures.

Figure I is a vertical longitudinal section 30 of my combined boiler and furnace, showing the essential features and the arrangement. Fig. II is a horizontal cross-section of the front portion of the boiler, intended particularly to show the semicircular form and arrangement of the combustion-chamber substantially over the center of the grate and entirely surrounded by the boiler.

In the figures, 1 indicates the foundation, 35 of brickwork or other suitable construction; 2, the ash-pit, provided with front and rear doors 3 for convenience in cleaning and for the admission of the air beneath the grate 4, of double or extra size, affording a large grate-surface by which a large amount of coal 45 may be fired and burned and a large amount of gas generated, which is instantly mixed with a regulable amount of air and completely consumed.

6 indicates the low furnace, having the 50 doors 7 and the top 8, in which is formed a chute 9 for the introduction of any suitable

fuel and the admission of air through one or more air-inlets 10, closed by slides 11.

15 is the combustion-chamber, having a contracted mouth 16 and arranged practically 55 over the center of the furnace and the grate and in the interior of the boiler, so that the combustion of the mixed gases and air therein takes place adjacent to the mouths of the tubes and is instantly communicated to the 60 water.

20 is the outer shell of the boiler; 21, the inner shell, forming the combustion-chamber; 22, the tubes; 23, the braces; 24, the smoke-flue; 25, the stay-bolts, connecting the outer 65 and inner shells, which are bent and connected, forming the circular leg 26, resting on the foundation and lined with the fire-brick 27.

By this peculiar construction and arrangement of furnace and boiler a large amount of 70 gas is generated and thoroughly heated and mixed with a regulable supply of air admitted through the inlets, and the gases unconsumed in the furnace are rapidly drawn through the contracted mouth into the combustion-chamber, where they are entirely consumed and a high degree of heat generated 75 in close contact with the water-surface at the mouths of the tubes and in the interior of the boiler.

The low furnace is compact and economical in construction and confines the air and gas, so that they are well mixed and the air brought in and maintained close to the fire to be at once thoroughly heated and avoid the danger of the admission of cold air 80

85 to chill the gas or the interior of the furnace. The low furnace alone would give an imperfect combustion; but by the combination therewith of the boiler inclosing the combustion-chamber the unconsumed and heated 90 gases mixed with the heated air are drawn from the furnace up through the contracted mouth, thereby thoroughly mixed and completely consumed in the combustion-chamber, as described.

95 This generator is suitable for any fuel, but particularly useful for refuse fuels and low-grade coals, from which by the large grate a large amount of gas is generated to be completely consumed, thus obtaining from low-grade coal practically perfect combustion and 100 a high degree of heat.

In construction my generator is compact and economical. I avoid the fire-door in the boiler-shell and also, by the short water-leg, the deterioration of plates resulting from sediment and defective circulation in a long water-leg.

Having thus described my invention, what I claim, and desire to secure by Letters Patent, is—

- 10 1. In a steam-generator, the combination with a low brick furnace, having a brick top at its front, of a double grate arranged therein, and a boiler supported on the brick by a short water-leg, having a vertical portion and 15 horizontal tubes extending into the vertical portion over the rear of the furnace and having an internal combustion-chamber in the vertical portion arranged substantially over the center of the grate and low furnace.
- 20 2. In a steam-generator, the combination with a suitable setting, of a grate having an enlarged surface supported on said setting, of the boiler extending over the rear of the grate and furnace, a suitable top extending 25 over the front of the grate, an outer shell to the boiler and a vertical inner shell arranged in the outer shell and forming a vertical combustion-chamber with a contracted mouth arranged substantially over the center of the 30 grate and furnace.
- 3. In a steam-generator, the combination with a suitable setting forming an ash-pit, of a grate having a large heating-surface arranged on the setting over the ash-pit, an 35 outer boiler-shell, tubes arranged therein extending over the rear of the grate and furnace, a top arranged adjacent to and extending over the front of the grate, whereby a low furnace is formed above the grate, an inner 40 shell arranged within the outer shell and in front of the tubes, forming a vertical combustion-chamber extending upwardly substantially over the center of the grate and furnace.
- 45 4. In a steam-generator, the combination with a suitable brick setting forming an ash-pit, of front and rear doors therein, a double grate affording a large heating-surface ar-

ranged on the setting above the ash-pit, a top extending inwardly over the front of the grate 50 and forming a low furnace, side and rear walls of refractory material, said top and side walls being formed with a chute and flues for the introduction of coal and the admission of air, slides at the outer ends of said chute and flues, 55 of an outer boiler-shell supported on the setting, horizontal flues arranged in said shell extending forwardly over the rear of the furnace, of an inner shell arranged within the front of the outer shell and having its lower 60 edge bent and connected to the lower edge of the outer shell to form a short, circular leg, resting on the brickwork of the setting, a fire-brick lining within said circular leg, said inner shell forming a vertical combustion- 65 chamber, having a contracted lower mouth and arranged over the center of the grate and adjacent to the forward ends of the tubes.

5. In a steam-generator, the combination with a suitable brick setting, of a double-size 70 grate affording a large heating-surface arranged on the setting above the ash-pit, a brick top having flues for the admission of the air extending inwardly over the front of the grate, suitable doors in said brick setting; of an outer boiler-shell supported on the setting, horizontal tubes arranged in said shell, of an inner shell arranged within the front portion of the outer shell and having its lower margin outwardly flanged and connected to the lower margin of the outer shell also outwardly flanged, forming a short water-leg resting on the brick setting with the rivets out of contact with the fire, and a fire-brick lining within said circular leg, said inner shell forming a vertical combustion-chamber 85 having a contracted lower mouth and arranged over the center of the grate and adjacent to the forward ends of the tubes.

In testimony whereof I have hereunto signed my name.

DAVID FITZGIBBONS. [L. S.]
